UNITED STATES PATENT OFFICE.

MAGNUS H. JOHANSON, OF ROCHESTER, NEW YORK.

METHOD OF FORMING BLADES.

1,356,628.

Specification of Letters Patent. Patented Oct. 26, 1920.

Application filed April 20, 1918. Serial No. 229,795.

To all whom it may concern:

Be it known that I, MAGNUS H. JOHANSON, a subject of the King of Sweden, residing at Rochester, in the county of Monroe and State of New York, have invented new and useful Improvements in Methods of Forming Blades, of which the following is a specification.

This invention relates to a method of and 10 mechanism for forming blades, particularly blades for safety razors.

The method and the mechanism for practising that method which I shall hereinafter describe, has for its object the production 15 of blades of novel form by an improved method which results in the making, at a single operation, from a suitable blank, of a blade having a single cutting edge, or a plurality of cutting edges; and in its extended development and preferred embodiment, a plurality of blades having a plurality of cutting edges, from a single blank.

In order that the method and mechanism may be clear to those skilled in the art, I 25 have illustrated in the drawings which accompany and form a part of this specification, the method and a mechanism by which the method may be practised.

It will be understood that such variations in the method as are clearly within 30 the range of my invention and comprehended in the claims appended hereunto, may be made without departing from the spirit of my invention.

35 In said drawings:

Figure 1 is a view of the blank upon which the method is practised and from which the blades are developed.

Fig. 2 is a view of the blank, partly in 40 section, to show a step of the method.

Fig. 3 is a view of the blank shown in Fig. 2, at right angles to the disclosure in that view.

Fig. 4 is a cross-sectional view to show 45 the blank and the development of the blade.

Fig. 5 is a view in cross-section to show a slightly different form of blank, which may be utilized in blade development, following the same method.

50 Fig. 6 is a view in cross-section of a completed blade, the blank being shown in dotted lines, this view being somewhat enlarged for clearness of illustration.

Fig. 7 is a view of a stack of blades, to 55 illustrate sale or transportation packaging.

Fig. 8 is a view in elevation of a mecha-

nism for developing the blades from a blank.

Fig. 9 is a plan view of the mechanism 60 shown in Fig. 8.

Fig. 10 is a detail view of the chuck head.

In practising the method which I have invented, I first cut blanks 10, of the length desired for the length of blade, from steel tubing, properly compounded to form good 65 razor steel or steel of such quality as is necessary for the blades which are to be produced. This tubing, in the embodiment here shown, is of a size in cross-section capable of producing two blades, but it is obvious 70 that its size may be increased, if desired, so as to produce, in accordance with my method, more than two blades.

The said blank 10 will then have formed on at least one of its ends, and preferably 75 both, suitable means for engagement with blade-locking instrumentalities on the safety razor holder, the present embodiment showing this means as notches 11, formed by a milling or other suitable operation. In the 80 present embodiment the notches 11 are shown as four in number, two at each end, and diametrically opposite each other and in alignment longitudinally, although it is obvious that the number of notches would be increased if more than two blades are to be produced from a single blank. Preferably, the end walls 12 of the notches 11 will be inclined as shown in Figs. 2 and 3, 85 in order that they may coöperate with the 90 blade-locking means when mounted in a blade-locking means when mounted in a 95 razor holder.

The blank, thus treated, is then subjected to such hardening and tempering processes 100 as are necessary or desirable to bring it to a proper temper for the formation of cutting blades, the blank in this form being of such weight and dimensions as that danger of distortion in tempering is eliminated and the difficulties experienced in tempering the 105 blades after they are formed and the thin cutting edges are shaped, is entirely done away with.

In this condition the blanks are then subjected to the operation illustrated diagrammatically in Fig. 4, in which the outline of the blank is indicated by the dotted lines 13, the blades 14 developed from the blank being indicated in full lines. The blade development is accomplished by removing, at 110 diametrically opposite points in the blank, sections of the blank wall, the present em-

bodiment showing the removal of lune-shaped segmental sections 15. The removal of these sections, which may obviously be of a form other than the lune-shaped sections illustrated, results in severing the blank into a plurality of parts longitudinally, with the opposite edge suitable for grinding and lapping to bring it to a sharp cutting edge 15^a, leaving a relatively heavy 10 central body portion 16 of sufficient rigidity to give an inherent stiffness to the blade as a whole, this central body portion 16 not being subjected to the grinding or other operation for removing the segmental sections, 15 and the inner semi-circular surface of the blank being untouched by the reducing or grinding instrumentalities.

The blank, when tempered, will have a hard skin or shell on the inside of the tube, 20 and this shell will form the extreme cutting edge of the blade when the wall sections of the blank are removed in the manner heretofore described, so that a blade will be provided in which the cutting edge will be of 25 proper temper to give a good razor edge.

It will be seen that the blades are in substantially finished condition, when developed as described, from the tubular blank; such slight stropping or lapping as is necessary to bring them to the final sharpened 30 condition being performed in any desirable manner, and such stropping or lapping will ordinarily be confined to the outer surface of the blade, although, if desired, the inner 35 edge of the blade may be slightly lapped or stropped to give it a finish.

In the development shown in Fig. 5, I have illustrated the application of my method to a semi-circular blank 18. In 40 this development the steps are identical with those described in connection with Fig. 4, the operation of reducing the blank comprising the removal of the half lune-shaped segments 19 shown in dotted lines, so that a 45 single blade having a plurality of cutting edges will be produced.

It is clear that blades developed in accordance with this invention may be cheaply and rapidly turned out, the operation on the 50 tubular blank developing two blades at a single operation. Furthermore, blades of this form may be closely packed or nested to form transportation or sale packages, as indicated in Fig. 7. Again, the substantially 55 semi-circular contour of the blade brings the cutting edges into such position relative to the blade support, that the cutting stroke will be more nearly parallel to the face and like that of the ordinary razor than is the 60 case with the horizontally arranged or slightly curved blades commonly in use.

It is obvious that this method of forming 65 blades is not limited to the formation of any particular number of blades from a blank, for the complete tube, or section of a tube,

as herein disclosed, may, by this method, be so manipulated as to produce two blades or a single blade, and it is clear that the number of blades which may be produced from a single tube or a half tube might be increased by grinding through the wall of the blank at two or more points in the circumference. For instance, by developing the 70 method, and by appropriate mechanism, a tube might be ground through and cutting edges produced at 90 degrees, or at 45 degrees about the circumference, so as to give four or eight blades. This extension of the method is, therefore, clearly within the 75 range of my invention.

While the method described may obviously be practised by the use of various tools and mechanisms, I have shown in Figs. 8 to 10, inclusive, one convenient form of mechanism for carrying out the method of 80 producing blades.

Referring to Fig. 8, which is an end view of a mechanism for practising the invention, 20 indicates a slide rest mounted upon a traversing body, not shown, to which slide 90 rest is secured a journal post 21, in which is mounted a rotating shaft 22 provided with any suitable driving means, such as pulley 23. The said shaft 22 has at its forward end a chucking member comprising the 95 chuck head 24 having the work-holding jaws 25, eccentrically disposed relative to the axis of the shaft 22, so as to lie concentric with a work-holding spindle 26, eccentrically placed relative to the axis of the rotating shaft 22. The spindle is of a diameter equal to the inside diameter of the tubular blank heretofore described, and of a length shorter than the length of that blank. At its rear end, adjacent the chuck head 24, 100 it is provided with notch-engaging projections 27 adapted to enter the notches in the blank and form an abutment therefor, said projections serving also to lock the blank against rotation on the spindle 26. The fingers 25 may be pivoted at 28 in the chuck head 24, which is cut away, as shown, to form recesses or seats for the fingers 25, with the fingers pivoted to the vertical wall of the recess, and springs 29 so disposed with 105 respect to the rear ends of the fingers as to tend always to close the forward ends of the fingers upon the blank and spindle. The forward end of the fingers will be provided with notch-engaging dogs 30, which will 110 drop into the notches at the end of the blank and lock it against longitudinal and also against rotative movement on the spindle.

With this construction, it will be seen that as the shaft 22 is rotated, the spindle 26 115 will have an orbital movement, so as to carry the spindle and the blank mounted thereon through a path eccentric to the center of rotation of the shaft.

Arranged adjacent the work-carrying 120

spindle, so as to intercept the path of movement of the blank on said spindle, is a reducing instrumentality, which, in the present instance, is shown as a grinding wheel 5 32 mounted on a suitable slide 33, positioned upon a suitable rest 34, which grinding wheel is provided with mechanism, not shown, but of any familiar type, for imparting a forward movement to the grinding wheel during the operation of reducing the blank, such forward movement of the grinding wheel being proportioned to give the requisite feed essential to a proper grinding off of the wall of the blank, and 10 15 this grinding wheel may be driven in any suitable manner, as by a shaft and pulley, not shown.

With this construction, it will be seen that the traversing chuck, with the blank mounted thereon, will move back and forth relative to the grinding wheel, and, by rotation of the shaft 22, bring that side of the blank farthest from the axis of rotation of the shaft into contact with the grinding wheel 25 on a curved line, which will result in removing from the wall of the blank the lune-shaped segments shown in Figs. 4 and 5. When one side of the blank has been shaped, it will be removed from the spindle and reversed, and a similar reduction of the opposite wall of the blank will be made, the 30 operation resulting in the development of two blades from a single blank.

Such departures from this disclosure as 35 are within the realm of mechanical skill and expediency, are to be taken as within the range of my invention.

I claim:

1. The step in the method of forming a 40 blade from a blank having a face which consists in so removing a portion of said blank on a curved line so as to form a face intersecting the first mentioned face.

2. The step in the method of forming a 45 blade from a blank having a curved face which consists in so removing a portion of said blank as to form a face intersecting the first mentioned face.

3. The step in the method of forming a 50 blade from a curved blank having a face which consists in so removing a portion of said blank as to form a face intersecting the first mentioned face.

4. The step in the method of forming a 55 plurality of blades from a single blank, which consists in so removing portions of said blank as to form a plurality of faces intersecting the face of said blank to develop cutting edges at the intersections of said faces.

5. The step in the method of forming a 60 plurality of blades from a single blank having a curved face, which consists in so removing portions of said blank as to form a plurality of faces intersecting the face of said faces.

said blank to develop cutting edges at the intersections of said faces.

6. The step in the method of forming a plurality of blades from a single curved blank having a face, which consists in so 70 removing portions of said blank as to form a plurality of faces intersecting the face of said blank to develop cutting edges at the intersections of said faces.

7. The method of forming blades which 75 consists in rotating a blank having curvilinear surfaces, intermittently contacting a portion of said blank with a cutting element to remove a section of said blank and form a face intersecting the first mentioned 80 surface.

8. The method of forming blades which 85 consists in intermittently contacting a portion of a blank having a curved surface with a cutting element to remove a section of said blank and form a face intersecting the first mentioned surface.

9. The step in the method of forming blades which consists in cutting through the 90 wall of a tubular blank to separate the blank into a plurality of blades and develop a plurality of cutting edges.

10. The step in the method of forming blades which consists in cutting through the 95 wall of a tubular blank on a curved line to separate the blank into a plurality of blades and develop a plurality of cutting edges.

11. The method of forming blades which 100 consists in rotating a blank about an axis and intermittently contacting a portion of said blank with a grinding element to remove a section of said blank to form a cutting edge thereon.

12. The method of forming blades which 105 consists in rotating a blank and contacting a portion of said blank with a cutting element to remove a section of said blank and form a plurality of cutting edges thereon.

13. The method of forming blades which 110 consists in rotating a curvilinear blank about an axis parallel to the axis of said blank and contacting a portion of said blank with a cutting element to remove a section of said blank to form a face intersecting the opposite face of said blank.

14. The method of forming blades which 115 consists in rotating a curvilinear blank about an axis parallel to the axis of said blank, intermittently contacting portions of said blank with a grinding element to form 120 a plurality of faces intersecting the opposite face of said blank.

15. The method of forming blades which 125 consists in rotating a tubular blank about an axis parallel to the axis of said blank intermittently contacting said blank at diametrically opposite points with a grinding element to form a plurality of faces intersecting the inner wall of said blank.

16. The method of forming blades which 130

consists in tempering a blank curved in cross-section; and cutting through the wall of said curved blank from the outside, so as to form a cutting edge of the blade from 5 the inner hardened skin of the curved blank.

17. The method of forming blades which consists in hardening a tubular blank; and cutting through the wall of the blank from the outside at such an angle as to leave the 10 inner hardened shell of the blank projecting to form a cutting edge.

18. The method of forming a plurality of blades from a single blank which consists in hardening a tubular blank, and cutting through the wall of the blank from the 15 outside at a plurality of points at such an angle as to leave the inner hardened shell of the blank projecting to form cutting edges.

In testimony whereof I have hereunto set 20 my hand.

MAGNUS H. JOHANSON.
